(57) **CLAIM**

The ornamental design for a hair curler, as shown and described.

DESCRIPTION

FIG. 1 is a front perspective view of a hair curler design showing my new design.

FIG. 2 is a front view of a hair curler.

FIG. 3 is a rear view of a hair curler.

FIG. 4 is a left side view of a hair curler.

FIG. 5 is a right side view of a hair curler.

FIG. 6 is a top view of a hair curler.

FIG. 7 is a bottom view of a hair curler.

FIG. 8 is a front perspective view of a hair curler.

FIG. 9 is an enlarged view of a hair curler taken from the circle part in FIG. 1; and,

FIG. 10 is an enlarged view of a hair curler taken from the circle part in FIG. 1.

The broken lines in the drawings depict portions of the hair curler that form no part of the claimed design.
